UNITED STATES PATENT OFFICE

2,539,939

MOBILE AGGREGATE-HANDLING UNIT

J Jack Willard and Carl L. Willard,
Lynwood, Calif.

Application May 1, 1947, Serial No. 745,160

1 Claim. (CL 214—2)

1

This invention relates to a mobile unit for handling aggregate or like material and contemplates a portable unit whereby a single operator, from a control position, can collect such material, weigh the same, transport it to a point of disposal and dump it at that point.

The primary object of the present invention is to provide an improved and efficient unitary structure for accomplishing the operations above stated.

Another object of the invention is to provide a combined unit of the character indicated which is mounted on the chassis of a conventional three-wheeled tractor truck in a compact arrangement whereby handling of aggregate is facilitated and flexible maneuverability of the unit is obtained.

Another object of the invention is to provide hopper means for a unit, as indicated, which is mounted on the chassis in such a manner that the aggregate received thereby is weighed and the weight indicated at a point on the unit and in the line of vision of the operator thereof.

Another object of the invention is to provide a mobile aggregate-handling unit which combines novel feeding means for the hopper thereof and said means being adapted to be moved from an operative to a non-operative road-clearing position.

A further object of the invention is to provide, in a unit as stated, novel and improved hopper-feeding means which embodies laterally arranged side-feeding elements whereby said feeding means efficiently removes material from a pile for discharge into a hopper.

Our invention also has for its objects to provide such means that are positive in operation, convenient in use, easily installed in a working position and easily disconnected therefrom, economical of manufacture, relatively simple, and of general superiority and serviceability.

The invention also comprises novel details of construction and novel combinations and arrangements of parts, which will more fully appear in the course of the following description. However, the drawings merely show and the following description merely describes one embodiment of the present invention, which is given by way of illustration or example only.

In the drawings, like reference characters designate similar parts in the several views.

Fig. 1 is a side elevational view of a mobile aggregate-handling unit embodying features of the present invention.

Fig. 2 is an enlarged cross-sectional view as

2

taken on the approximate planes of line 2—2 of Fig. 1.

Fig. 3 is an elevational view as seen from the material feeding end of the unit.

5 Fig. 4 is a semi-schematic plan view, to a reduced scale.

The mobile aggregate unit which is illustrated comprises, generally, a wheel-mounted chassis 5, a power plant 6 for driving the same, a hopper 7, a support frame 8 carried by the chassis, scale or weighing means 9 connecting said hopper and support frame, a dumping gate 10 for the hopper, and a feeding device 11 including a scoop 12 carried by the chassis and support frame for feeding aggregate from a pile into said hopper.

10 The chassis comprises a frame having sides 13, a front end 14, rearward inwardly angled portions 15, and an upwardly and rearwardly curved goose neck 16. The latter, by means of a fork 17, pivotally mounts a rear wheel 18 which nests in said goose neck and is steerable through the medium of a steering lever 19 and suitable power advantage gearing 20. A pair of front wheels 21 support the front end of the chassis and are mounted 15 on end spindles of a fixed axle 22 secured to chassis end 14.

15 The power plant 6 is generally conventional and includes an engine 23, a drive 24 from said engine, a differential 25 at the end of the drive, and a pair of chain drives 26 driven from the differential and connected to drive the wheels 21.

20 The hopper 7 has an open top 27 and is rectangular in plan. The top of the hopper is framed by side walls 28, rear wall 29 and front wall 30. The latter extends vertically from the top opening 27 to the gate 10, whereas the side and rear walls from a short distance below the top opening, are inwardly sloped to form respective converging walls 31 and 32. It will be seen that the hopper is quite wide at the top and converges 25 toward gate 10 to suitably fit into chassis 5 with ample clearance with chassis sides 13. The bottom of the hopper has suitable clearance spacing from the ground line.

25 It will be seen from Fig. 1 that the chain drive 26 allows for a forward spacing of wheels 21 and axle 22 thereof relative to differential 25 and that hopper gate 10 is disposed between said axle and differential. The advantages of this stable and compact arrangement are three-fold, viz., the weight of the hopper and contents are cradled between the three wheels of the chassis, the gate 10 is disposed between wheels 21 and in desired proximity to the ground so that no parts of the machine are in the line of discharge of material from the hopper, and the mass and weight of the

chassis and hopper and its contents are disposed on one side of wheels 21 with the mass and weight of the feeding device 11 on the opposite side.

The support frame 8 is formed to surround the hopper and consists of an encircling frame 33 for the upper portion of the hopper and suitable struts 34 spacing frame 33 from chassis 5. The support frame 8 is so formed that no portion thereof is in physical contact with the hopper, said frame comprising an upper extension of 10 the chassis 5.

The weighing means 9 is generally typical of such means and is connected to the frame 8 and to brackets 35 provided on the hopper. The latter is thus suspended from the frame and, according to the weight of material in the hopper, influences the elevated or depressed position of arms 36 and, through said arms, the angular position of balance arm 37. The latter, by means of a hook and eye 38, is connected to balance means within box 39 to influence the angular position of a pointer 40 of frame 41. The latter is so positioned that an operator in a seat 42 can readily view the same and, thereby, be enabled to manipulate the proper controls to stop feed of material to the hopper when the position of pointer 40 indicates that said hopper has received the proper amount or weight of material.

The dumping gate 10 is shown as a pair of pivoted members 43, normally closing the discharge opening of the hopper. By means of suitable linkage 44, a control handle 45, accessible to the operator on seat 42, can effect pivoting of members 43 at the point of discharge of the material in the hopper.

The feeding device 11 comprises a bucket elevator 46, carried by a frame 47, arranged at the front of the chassis 5. The frame 47 extends at a rearward angle upwardly towards and above the hopper. A pair of braces 48 extending from the chassis 5 and frame 8 mount said elevator on a pivot 49 intermediate the length of frame 47. Stop braces 50 engage the frame 47 below pivot 49 to hold the same at a desired operative angle. The frame 47 has no tendency to pivot of itself since it is heavier at the bottom and, in operation, the thrust, when the elevator is picking up material from a stock pile, is in a direction pressing said frame 47 against the stop braces.

The elevator 46 comprises upper and lower shafts 51 and 52, respectively, a pair of spaced sprockets 53 on each shaft, an endless chain 54 trained over the respective sprockets of each pair, and a plurality of scoop buckets 55 mounted across the chains. A drive is provided for the elevator and comprises a drive shaft 56 extending along one side of frame 8, a clutch-included jack shaft 57, a driving connection 58 between said shaft and power plant 6, and a driving connection 59 between said shaft and drive shaft 56. The forward end of the latter shaft, within a housing 60, has suitable gearing to drive a transverse stud shaft 61, which, through the medium of a chain and sprockets 62 and a chain and sprockets 63 drives the upper shaft 51 of the elevator. The upper sprocket of chain drive 62 and the lower sprocket of chain drive 63 are rotatably wound on a pivot 49 and said sprockets are operatively connected. In this manner, the elevator is adapted to be swung on its pivot without disturbing the driving connections therefor. Suitable hoods 64 and 65 are provided to house said chain drives.

It will be evident that the driving means above described, operates the elevator, by means of en-

gine 6, to cause the buckets 55, successively, to remove material from a stock pile and discharge the same into the open top 21 of the hopper. To insure that said material will properly be directed into the hopper, a guide plate 66, connected to frame 47 by suitable brackets 67, is provided, said plate receiving the material from the buckets and directing the same into the hopper.

To render the feed more flexible and reduce the "back and fill" movements of the machine, lateral feeding means are provided. Said means is shown as a helical member 68 on each lateral extension of shaft 52 and so formed as to gather and feed material toward the buckets 55. Inasmuch as said members 68 reside within the lateral dimensions of the machine, they provide a simple and effective means for feeding material laterally toward the buckets with a minimum forward movement of the machine.

The elevator 46 is kept clear of the ground line to obviate its snagging on uneven projections thereof. The scoop 12 is provided to gather such material as the elevator would ordinarily leave behind. Said scoop comprises a curved blade 69, transversely co-extensive with the elevator and lateral feeding helices 68, and pivotally mounted at 70, by means of arms 71, on chassis 5. It will be seen that material received by the scoop is readily picked up by the buckets 55 to effect a clean diminishing of the stock pile.

It will be noted that chains 72 connect the scoop arms 71 and the elevator frame 47. These chains are provided for lifting the scoop to clear the ground when it is desired to transport the machine, as over a road. By tilting the elevator on its pivot 49, the lower end thereof is raised to increase its clearance with the ground and, through chains 71, upwardly tilt the scoop on its pivot 70 to raise the same from the ground.

While we have illustrated and described what we now regard as the preferred embodiment of our invention, the construction is, of course, subject to modifications without departing from the spirit and scope of our invention. We therefore, do not wish to restrict ourselves to the particular form of construction illustrated and described, but desire to avail ourselves of all modifications that may fall within the scope of the appended claim.

Having thus described our invention, what we claim and desire to secure by Letters Patent is:

A machine of the character described comprising a chassis having wheels at opposite sides of its front end and a steering wheel at its rear end, a power plant carried by said chassis in front of the rear wheel having means associated with it for transmitting motion to the front wheels, a frame mounted over said chassis, a hopper shiftable vertically through said frame and having a discharge spout at its bottom extending downwardly through the chassis, a conveyor mounted at the front of said chassis forwardly of the front wheels and serving to carry material upwardly and deposit the material in the hopper, a seat carried by said chassis back of said frame and facing forwardly, a closure for said spout, the closure and the power plant each having control mechanism disposed in front of said seat in position to be readily accessible to an operator occupying the seat, bars at opposite sides of said frame extending longitudinally thereof, brackets pivotally supporting said bars for transverse movement and extending inwardly from the bars, said hopper 75 being suspended from said brackets, arms ex-

tending towards each other from said bars back of said hopper, a balance bar extending transversely of the rear end of said frame over said arms, said arms having their inner ends connected with said balance bar and imparting tilting movement to it in response to downward movement of the hopper by the weight of material in the hopper, and indicator means for the scale mounted upon the rear end of said frame in view of a person occupying said seat and connected with 19 and actuated by movements of the balance bar.
